UNITED STATES PATENT OFFICE.

HARRY B. SMITH, OF NEW YORK, N. Y.

BLANK FOR PAPER BOXES.

SPECIFICATION forming part of Letters Patent No. 634,507, dated October 10, 1899.

Application filed May 8, 1899. Serial No. 715,999. (No model.)

To all whom it may concern:

Be it known that I, HARRY B. SMITH, a citizen of the United States, residing at New York, (Brooklyn,) in the county of Kings and State of New York, have invented certain new and useful Improvements in Blanks for Paper Boxes; and I do hereby declare the following to be a full, clear, and exact description of the invention, such as will enable others skilled in the art to which it appertains to make and use the same.

My present invention relates to certain new and useful improvements in box-blanks, and more particularly to blanks for forming paper boxes.

It is the prime object of the invention to provide an extremely cheap and easily-constructed blank for forming paper boxes having curved or rounded corners, the bottom, ends, and sides of the box being formed from a single blank, and the wings forming said ends and sides being constructed in such manner as to form when folded up into position a smooth unbroken surface around the entire outer circumference of the box, no overlapping parts whatever being present in the structure, which is one of the essential and distinguishing features of the invention.

The demand for a paper box having curved or rounded corners is very great at the present time; but as heretofore constructed it was impossible to obtain such a box at a price low enough to enable its general use in connection with articles sold at a nominal price. Furthermore, boxes now upon the market having rounded corners, so far as I am aware, either have crimps or folds at the corners or are formed with overlapping portions or edges, which render such corners uneven, cumbersome, or bulky, and otherwise detract generally from the neatness of the box.

Briefly stated, my invention comprises a box-blank made from paper or card board and consisting of a body portion of any desired shape having its corners rounded or curved and provided with side and end wings or flaps which have the opposite ends thereof cut off or removed to such a degree or extent as that when folded up to form a box the adjacent edges of said wings or flaps will abut against each other to form a close fit, but will not overlap each other, thus producing a smooth

and continuous unbroken surface around the outer circumference of the box.

In order to enable others to construct box-blanks and boxes in accordance with my invention, I will proceed to describe the same in detail, reference being had for this purpose to the accompanying drawings, wherein—

Figure 1 is a plan view of one of my improved box-blanks. Fig. 2 is a perspective view of a box formed from one of my blanks. Fig. 3 is a transverse sectional view of the blank, taken on the line xx of Fig. 1.

Referring now to the drawings, the reference-numeral 1 designates the body of the blank, which in the present instance is shown as being rectangular in shape; but I wish it understood that I do not confine myself to any particular shape of blank, for obviously the shape and general outline of the blank may be varied at will without departing from the true spirit of the invention, the novel features of which I will now describe.

The corners of the blank 1 are rounded or curved, as at 2, and the sides and ends of the blank are provided with integral wings or flaps 3 3 and 4 4, respectively, the body of the blank being scored, cut, or creased along the lines 5 5 and 6 6, where the said ends and side 8 0 wings or flaps join the said body of the blank, to facilitate the upward bending of said wings or flaps during the formation of the box. The opposite free ends 7 and 8 of the side and end wings, respectively, are cut off, so that the maximum length of each wing will be slightly less than the corresponding width and length, respectively, of the sides and ends of the body portion of the blank, whereby when the said wings are folded up in the position shown in Fig. 2 to form the box and the free ends 7 and 8 of said wings are bent around the curved or rounded corners 2 the adjacent edges of the free ends of said wings will just meet and abut against each other to form a close fit, but will not overlap, and this I consider as the important and novel feature of the invention. After the wings have been folded up in position to form the box they can be retained in such position in any suitable manner, as by metal corner-clips, short strips of paper pasted or glued to the corners, or by a surrounding strip of covering-paper, which will be pasted entirely around the outer cir-

cumference of the box, and owing to the fact that a clean flush joint is formed at the rounded corners, no overlapping or crimped parts being present, a smooth unbroken surface is 5 thus provided which adds greatly to the neatness and attractiveness of the box.

As heretofore stated, I do not wish to be understood as limiting myself to any particular form or shape of blank, for obviously the 10 general shape and configuration of the blank may vary to suit the demands without departing from the spirit of my invention, the essential feature of which is to provide a box with rounded corners and a continuous smooth 15 outer circumference entirely free from projections or undulations, such as are usually present in boxes having crimped or overlapping portions at the corners.

What I claim, and desire to secure by Letters Patent, is—

1. A paper-box blank formed from a single sheet, comprising a body portion having rounded corners and integral side and end wings, the maximum length of said wings being slightly less than the maximum length of 25

the sides and ends respectively of the body portion of the blank, so that when said wings are folded up into position for the formation of the box, the adjacent edges of said side and end wings will abut but not overlap, substantially as described. 30

2. A paper-box blank formed from a single sheet, comprising a rectangular body portion having rounded corners and integral side and end wings, with lines of scoring or creasing 35 at the points of connection between the wings and body of the blank, the maximum length of said wings being slightly less than the maximum length of the sides and ends respectively of the body portion of the blank, so 40 that when said wings are folded upward into position for the formation of the box, the adjacent edges of said side and end wings will abut to form a close joint but will not overlap.

In testimony whereof I affix my signature 45 in presence of two witnesses.

HARRY B. SMITH.
